W. L. SMITH.

MOTION PICTURE FILM CABINET.

APPLICATION FILED APR. 17, 1914.

1,144,736.

Patented June 29, 1915

UNITED STATES PATENT OFFICE

WILLIAM L. SMITH, OF DECATUR, ILLINOIS, ASSIGNOR OF ONE-HALF TO JAMES A. GREER, OF DECATUR, ILLINOIS.

MOTION-PICTURE-FILM CABINET.

1,144,736.

Specification of Letters Patent. Patented June 29, 1915.

Application filed April 17, 1914. Serial No. 832,418.

To all whom it may concern:

Be it known that I, WILLIAM L. SMITH, a resident of Decatur, county of Macon, and State of Illinois, have invented certain new and useful Improvements in Motion-Picture-Film Cabinets, of which the following is a specification.

My invention relates to improvements in film cabinets and is particularly directed to the provision of a cabinet having a plurality of compartments, each adapted to receive a motion picture film, the cabinet as a whole being fire proof.

A further object is the provision of such a device having film holders pivotally mounted so as to be moved to a closed position in each compartment whereby the film is protected against fire or damage from other sources, and also being adapted to be moved to an open position where the film is located in a position convenient for manipulation.

A further object is the provision of a film holder in each compartment of such a cabinet pivotally mounted and counterbalanced so that each holder may be moved to and from its open and closed positions with a minimum expenditure of energy, gravitation assisting in the movement in each direction.

Further objects include improvements in details of structure whereby a simple, cheap and efficiently operative fire proof film cabinet is provided.

To the accomplishment of the foregoing and such other objects as may hereinafter appear, my invention consists in the construction, arrangement and combination of parts hereinafter described and then sought to be defined in the appended claims, reference being had to the accompanying drawings forming a part hereof, and which show merely for the purpose of illustrative disclosure, a preferred embodiment of my invention, it being understood that various changes may be made in the construction in practice within the scope of the claims without digressing from my inventive idea.

In the drawings, Figure 1 represents a front elevation, one of the holders being shown in open position and one being shown broken away to facilitate the disclosure. Fig. 2 is a vertical section through the cabinet showing a film holder with a film therein in its open position in full lines and

in its closed position in dotted lines. Fig. 3 is a section taken on the lower part of line 3-3 of Fig. 1 through the bottom of one of the film holders and cabinet to show the manner of pivoting the film holder. Fig. 4 is a similar view taken on the lower part of line 4-4 of Fig. 1 illustrating the form of the front wall of the cabinet. Fig. 5 is a section taken on line 5-5 of Fig. 3 illustrating in detail certain features of construction.

In the drawings, the same reference characters are used to designate like and corresponding parts.

It is required by underwriters' regulations and statutes and ordinances in various places that the films in motion picture houses be kept in fire proof cabinets as they are of a highly inflammable character. It is the purpose of my invention to provide such a cabinet which will contain a plurality of films in separate compartments, each compartment having its own closure, so that only one film is exposed at the most and should any one film catch fire, the fire will be confined to its compartment and will not endanger or damage the films in the other compartments. It is a further purpose of my invention to provide film holders for each of the compartments which are so pivotally mounted and balanced that they will operate with facility, being assisted by the action of gravity, and further, in which the film will be projected toward the front when they are open so as to be in a position convenient for manipulation.

Referring now to the drawings, the numeral 1 designates the cabinet as a whole, which as shown is substantially rectangular in shape, having the solid sides, back, top and bottom walls as shown. The front wall 2 is straight for more than half of its length and is then curved inwardly as indicated at 3 in Fig. 4, and then downwardly as indicated at 4, same figure. This front wall is cut out as indicated at 5 to provide a plurality of spaced openings therein, each opening forming the entrance to the compartment 6 which is provided by the partitions 7, which extend between the front and back walls and the top and bottom walls, whereby each compartment is completely isolated and separated from the other.

Mounted in each of the compartments 6 is the film holder 8, which is of peculiar shape

and construction as shown in the various views of the drawing. It comprises the bottom member 9, part of which is semi-circular as shown at 10, merging into the straight 5 portion 11, whereby it corresponds in conformation to the front portion 2 of the cabinet, the straight portion and part of the curved portion providing the closure for the opening 5 when the film holder is in its 10 closed position as shown to the left in Fig. 1 and in dotted lines in Fig. 2, this portion of the bottom of said film holder extending laterally from the sides 12 as indicated at 13 so as to provide flanges to extend beyond the 15 edges of the opening 5 when the holder is in its closed position. Each holder has its bottom members extended as shown at 14, Fig. 3, and formed with the eye 15 to receive the transverse rod member 16 which is held 20 on the inside of the bottom member of the cabinet by means of the strap 17. This extension 14 is strengthened by means of the bracing member 18 as shown in Figs. 2 and 3. The side members 12 of each holder are 25 cut out as shown, so that when the holder is in its open position, the reel will be exposed sufficiently so as to be grasped conveniently, as shown in full lines in Fig. 2. The pivotal connection for each film holder is so positioned that when a reel is positioned therein, 30 it is balanced so that the film holder will be moved to and from its open and closed position, by giving it a slight initial impulse or impetus, the handle 19 being provided on each film holder for that purpose.

It is obvious therefore, that I have provided a cabinet which may be built in various sizes according to the requirements of the user, having a plurality of compartments, 40 each having a pivotally mounted holder adapted to hold a motion picture film reel, each compartment being separate from the other so as to be isolated to prevent communication of fire from one compartment to the other.

The cabinet is preferably made of sheet metal, but any other suitable fire proof material may be utilized, as is obvious, the invention being directed to the construction as 50 hereinbefore described.

What I claim is:

1. A fire-proof cabinet of the character described, having a plurality of entirely separate compartments, a holder in each compartment, each holder having a bottom portion and sides and being pivotally mounted, part of the bottom portion of each holder forming the closure for its compartment when the holder is in its closed position so that the 60 contents of each holder are entirely separated from the contents of the others.

2. A fire-proof cabinet of the character described, having a plurality of partitions therein extending from the top to the bottom 65 walls and from the rear to the front walls,

whereby a plurality of entirely separate compartments is provided, the front wall of each compartment being open, a film holder pivotally mounted in each compartment and having a bottom and sides, part of said bottom being adapted to serve as a closure for the opening into its compartment when the film holder is in its closed position so that the contents of each holder are entirely separated from the contents of the others.

3. A fire-proof cabinet of the character described, having a plurality of partitions therein extending from the top to the bottom walls and from the rear to the front walls, whereby a plurality of entirely separate compartments is provided, the front wall of said cabinet having an opening into each compartment and being curved in its lower portion, a film holder pivotally mounted in each compartment and having side walls and a bottom member, said bottom member being curved for a portion of its length and having a straight portion merging into said curve, said straight portion and part of the curved portion of the bottom member serving as the closure for its compartment when the film holder is in its closed position so that the contents of each holder are entirely separated from the contents of the others.

4. A fire-proof cabinet of the character described having a compartment therein, a film holder pivotally mounted in said compartment, said holder having side walls and a bottom member, said bottom member being curved for a substantial portion of its length whereby it is adapted to receive a film reel and also being straight for a portion of its length, said straight portion and part of the curved portion of the bottom member of said holder being adapted to serve as a closure for said compartment when said film holder is in its closed position.

5. A fire-proof cabinet of the character described having a compartment therein, a film holder pivotally mounted in said compartment, said holder having side walls and a bottom member, said bottom member being curved for a substantial portion of its length whereby it is adapted to receive and fit a film reel and also being straight for a portion of its length, said straight portion and part of the curved portion of the bottom member of said holder being adapted to serve as a closure for said compartment when said film holder is in its closed position, the pivotal mounting of said film holder being provided by forming the bottom member thereof with an extension having an eye and a rod secured to said cabinet and passing through said eye.

6. A fire-proof cabinet of the character described having its front wall provided with a plurality of openings and curved inwardly in its lower portion, a plurality of

- partitions extending from the top to the bottom walls and from the rear to the front walls and dividing said cabinet into a plurality of entirely separate compartments, the 5 openings in said front wall providing the entrances into said compartments, a film holder for each compartment, said holder including side walls and a bottom member, said bottom member being curved for a substantial portion of its length and also having a straight portion, said straight portion and part of the curved portion of said bottom member corresponding in shape to said front wall of the cabinet, whereby when the film 10 holder is in its closed position a closure will be provided for the opening into its compartment and the contents of each film holder will be held entirely separate from the contents of the other film holders, each 15 of said film holders being pivotally mounted.
7. A cabinet of the character described having its front wall provided with a plurality of openings and curved inwardly in its lower portion, a plurality of partitions 20 dividing said cabinet into a plurality of separate compartments, the openings in said front wall providing the entrances into said compartments, a film holder for each compartment, said holder including side walls and a bottom member, said bottom member being curved for a substantial portion of its length and also having a straight portion, said straight portion and part of the curved portion of said bottom member corresponding 25 in shape to said front wall of the cabinet, whereby when the film holder is in its 30 closed position, a closure will be provided for the opening into its compartment, the part of said bottom member of each holder which forms the closure being extended 40 beyond the side walls thereof to provide flanges which extend beyond the edges of the opening into its compartment, each of said film holders being pivotally mounted.
8. A fire-proof cabinet of the character 45 described, having a plurality of partitions therein whereby a plurality of entirely separate compartments is provided, a film holder for each compartment, said film holder having side walls and a bottom member, said 50 bottom member being curved for a substantial portion of its length and being straight for the remainder of its length, said straight portion and part of the curved portion of said bottom member being adapted to provide a closure for its compartment, said film 55 holders being pivotally mounted in said compartments and so balanced that their movements to and from their open and closed positions will be materially assisted by 60 gravitation, the curved portion of said bottom member of each holder being so formed as to receive and fit a film reel and also adapted to slightly project the film reel when the holder is in its open position. 65
- In testimony whereof I sign my name in the presence of two subscribing witnesses.

WILLIAM L. SMITH.
